UNITED STATES PATENT OFFICE

MYRON GOODWIN, OF BERWICK, MAINE.

DESIGN FOR A POLISHER.

46,526.

Specification for Design.

Patented Oct. 13, 1914

Application filed May 29, 1914. Serial No. 841,920. Term of patent 14 years.

To all whom it may concern:

Be it known that I, MYRON GOODWIN, a citizen of the United States, residing at Berwick, in the county of York and State of Maine, have invented a new, original, and ornamental Design for a Polisher, of which the following is a specification, reference being had to the accompanying drawing, forming part thereof.

Figure 1 is a perspective view of a polisher

showing my design, and Fig. 2 is a plan view thereof.

I claim:

The ornamental design for a polisher, as shown.

MYRON GOODWIN.

Witnesses:

FRED H. ROBERTS,
ARTHUR G. RANDALL.
